(57) CLAIM

The ornamental design for an egg holder, as shown and described.

DESCRIPTION

FIG. 1 is a front perspective view of an egg holder, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view showing the egg holder in a front state; and,

FIG. 10 is a perspective view showing the egg holder in a rear state.

The broken lines shown in FIGS. 9 and 10 depict environmental subject matter that forms no part of the claimed design.
